DESIGN FOR A STOVE

William R. Chamberlain, Mount Vernon, N. Y.

Application October 31, 1940, Serial No. 96,236

Term of patent 14 years

To all whom it may concern:

Be it known that I, William R. Chamberlain, a citizen of the United States, residing at Mount Vernon, in the county of Westchester and State of New York, have invented a new, original, and ornamental Design for a Stove, of which the following is a specification, reference being had to the accompanying drawing forming part thereof.

The figure is a perspective view of a stove showing my new design. The side and end of the stove which are not shown in the drawing are substantially plain.

I claim:

The ornamental design for a stove, as shown and described.

WILLIAM R. CHAMBERLAIN.
